UNITED STATES PATENT OFFICE.

ALBERT FAYEL WHEELER, OF KANSAS CITY, MISSOURI.

POCKET-BILLIARD OR POOL TABLE APPLIANCE.

1,200,062.

Specification of Letters Patent. Patented Oct. 3, 1916.

Application filed March 24, 1916. Serial No. 86,435.

To all whom it may concern:

Be it known that I, ALBERT FAYEL WHEELER, a citizen of the United States, residing at Kansas City, in the county of

5 Jackson and State of Missouri, have invented certain new and useful Improvements in Pocket-Billiard or Pool Table Appliances, of which the following is a specification.

10 This invention relates to pool or billiard ball racks particularly adapted to be applied directly to pool or billiard tables for automatically collecting and selectively racking the balls as the latter are shot into 15 the pockets of the table.

One object of the invention is to provide a device of the nature stated which may be easily and readily applied to existing pool and pocket billiard tables without any 20 change in the structure of the tables and without the necessity of employing an expert mechanic to perform the task.

Another object resides in the provision of a rack of the nature stated embodying 25 among other characteristics structural features whereby the balls may be directed selectively onto different shelves and retained temporarily thereon, or passed entirely through the appliance during the progress 30 of the game.

Another object is to provide a rack of the character stated wherein each player may select one of a plurality of shelves on which the balls shot into the pockets may be collected and retained during the progress of 35 the game, so that at the end or during the game, by reference to the shelf of each player, the number of balls made by each player may be easily and readily determined, or the aggregate numbers of the balls calculated, the structure being such that, while the balls are not liable to roll off of the shelves, one or more balls may be readily taken from over the outer longitudinal edge 40 of a shelf in the event that it should have been directed onto the wrong shelf.

Another object is to provide an appliance of the nature stated, embodying a casing provided with a plurality of superimposed 45 shelves having communication at one of their ends with a passageway and at their opposite ends having discharge openings, with means constructed and arranged to divert a ball or balls from the passageway 50 onto the various shelves interchangeably and

from which shelves they may be discharged separately or simultaneously through the instrumentality of gates which may be actuated separately or together.

A still further object resides in the provision of an appliance of the nature stated, embodying among other characteristics, a plurality of shelves adapted to receive and retain balls temporarily, the appliance including a guide-way which is normally maintained closed, and a passageway interposed between the guide-way and the plurality of shelves, with means disposed in the path of the guide-way for manipulation to release simultaneously balls from the guide-way and permit them to enter the passageway and be diverted from the passageway onto the shelves interchangeably.

With the above and other objects in view, the present invention consists in the combination and arrangement of parts herein-after more fully described, illustrated in the accompanying drawings, and particularly pointed out in the appended claims, it being understood that changes may be made in the form, size, proportion and minor details without departing from the spirit or sacrificing any of the advantages of the invention.

In the drawings:—Figure 1 is a perspective view of my invention illustrated as applied to a pocket billiard or pool table. Fig. 2 is a vertical longitudinal sectional view through my improved rack. Fig. 3 is a horizontal sectional view. Fig. 4 is a vertical transverse sectional view on the line $x-x$ of Fig. 2. Fig. 5 is a view similar to Fig. 4 taken on the line $y-y$ of Fig. 2. Fig. 6 is a detail plan view of one of the slides operable for projection into and out of the passage 90 between the guide-way and the shelves designed to divert balls from the passage-way onto one of the racking shelves.

Referring now more particularly to the accompanying drawings, the reference character A indicates a pocket billiard or pool table of any well known or improved variety, provided with pockets 10 which have communication with a run-way 11 usually provided for the purpose of leading the balls 105 12' to one end of the table, and the present invention is designed to be substituted for the contrivance generally used at the outer end of the run-way for collecting the balls.

To the above end the reference character 110

B indicates the casing of my improved rack provided with sides 12 and 13, and which is open at its front and at its rear. This casing may be composed of any suitable material and it may be secured to the table A in any suitable manner. A vertical partition 14 is arranged within the casing adjacent the front thereof, extending from side to side of the casing. This partition is provided adjacent the side 12 of the casing with alining vertical slots 15, 16, 17 and 18 and adjacent the side 13 of the casing the partition 14 is provided with a plurality of vertically alining horizontal slots 19, 20 and 21. These slots are provided for a purpose presently explained.

A horizontally disposed shelf 22 is connected to the sides of the casing A near the bottom of the latter between the front edge 20 of the casing and the aforesaid vertical partition 14. A horizontal partition 23 is arranged in the upper portion of the casing and supported between the sides of the latter directly over the top of the vertical partition 14. On this horizontal partition 23 are curved walls 24 and 25 spaced apart to form a guide-way C which communicates with the aforesaid run-way 11 leading from the various pockets of the table so as to convey the balls 12' to a circular or other opening 26 formed in the aforesaid horizontal partition 23 adjacent the side 13 of the casing B, there being a slightly inclined or beveled facing 27 on the bottom of the guide-way C to facilitate travel by gravitation of the balls 12' through the same toward said opening 26.

A vertical partition 28 is arranged in the front part of the casing B slightly spaced from the side 13 of the casing and which is connected to the aforesaid vertical partition 14 and to the partition 23 and shelf 22, respectively, forming a passage-way D for the balls 12' which, in this particular instance, drop into the passage-way D from the guide-way C through said opening 26. The passage-way D, while shown as arranged to permit the balls to drop thereinto, may be arranged differently but, in the preferred form of my invention, this passage-way is to be arranged as herein shown and described.

Connected to the vertical partition 28 and the side 12 of the casing B are shelves 29, 30 and 31, each of which has its upper face 55 slightly inclined toward the side 12 of the casing and also slightly inclined from its outer to its inner edge, having its end adjacent the side 12 of the casing concaved, as shown, with the concaved portions of the shelves provided with circular or other openings 32, 33, and 34, respectively. The shelves 22, 29, 30 and 31 may be otherwise formed and disposed so long as provision is made to prevent the balls accidentally rolling over the outer edges of the shelves, if

desired, and so long as provision is made to provide for a gravitating movement of the balls on the shelves from the passage-way D toward the openings in the shelves adjacent the side 12 of the casing. The spaces between these shelves 22, 29, 30 and 31 communicate with the aforesaid passage-way D through openings 28' in the partition 28.

A vertically sliding gate 35 is mounted in the guide-way C. The walls 24 and 25 of the guide-way may be provided with slots 36 in which the gate 35 may slide. This gate is designed to check the movement of the balls 12' in the guide-way C as they enter the latter from the run-way 11 until it is desired to permit the balls to pass through the opening 26 into the passage-way D. This gate 35 is held normally in closed position by means of a lever 38 pivoted at 39 in the casing B and to which said gate 35 is connected at 40, the lever 38 passing through a slot 41 in the wall 24 of the guide C and which extends at its outer end over the aforesaid opening 26 in the partition 23. The free end of this lever 38 is enlarged, as indicated at 38', for the purpose of weighting the outer end of the lever to hold the same normally down and thereby maintain the gate 35 normally closed, thereby obviating the use of a spring or other similar element to maintain the gate normally closed and to insure the lever 38 assuming its normal downward position, although, if desired, a spring may be substituted for the weighted end 38'.

To arrest movement of the balls 12' on the various shelves 22, 29, 30 and 31, I provide a gate for each shelf. These gates are indicated at 42, 43, 44 and 45 and are 105 adapted to swing in the respetive vertically disposed alining slots 15, 16, 17 and 18, the inner ends of these gates 42 to 45, inclusive, being pivoted at 46 in a suitable support 47 confined within the casing and disposed in the rear of the aforesaid vertical partition 14. These gates have their outer ends slidably mounted in slots 48, 49, 50 and 51, respectively, of an operating device, preferably in the form of a strip 52 slidably mounted 110 in the upper and lower brackets 53 and 54, respectively, and which may be slidably manipulated in said brackets through the convenience of a knob or other suitable device 55 located preferably at the upper 115 end of the strip 52. By virtue of the slots 48 to 51, inclusive, in the strip 52, each of the gates 42 to 45, inclusive, may be operated singly by simply shifting the respective gate on its pivot and thereby permitting 120 the ball or balls on a respective shelf to drop through the corresponding discharge opening adjacent the side 12 of the casing. For instance, if the gate 42 be shifted in the slot 15 on its pivot 46, the balls 12' will be 125 130

permitted to run off of the shelf 29 and through the opening 32 therein and drop through the openings 33 and 34 of the shelves 30 and 31, respectively, onto the shelf 22 and finally pass out through the opening 56 in the side 12 of the casing into a suitable receptacle, which may be located adjacent said opening 56. A strip 56' may connect the shelves 31 and 22 at the front 5 between the side 12 and the strip 52 to prevent accidental bouncing of the balls off the outer longitudinal edge of the shelf 22. It will, therefore, be clear that balls on the shelf 30 may be similarly released therefrom so that they may pass out through the opening 56 in the side 12 of the casing. If it be desired to release all of the balls from all of the shelves, all of the gates may be raised simultaneously by an upward 15 movement of the strip 52, which, when released, will drop to normal position, thereby preventing the escape of balls from the shelves as will be understood.

It is now understood how the balls are released from the various shelves and it will be explained how the balls are diverted from the passage-way D onto the respective shelves. To this end I provide means for releasing the balls from the guide-way C to 25 permit them to enter the passage D and simultaneously project means into the passage-way D to divert the balls from the passage-way selectively onto the shelves according to which shelf it is desired to divert the balls. This may be accomplished by disposing in the rear of the vertical partition 14 and at a right angle thereto a vertical partition 57. Connected to the rear edge of the vertical partition 57 and the adjacent side 13 of the casing are sets of guides each including upper and lower strips 58 and 59, the space between the guide strips 58 and 59 of each guide being arranged in horizontal alignment with the aforesaid 35 horizontally disposed slots 19, 20 and 21 in the vertical partition 14. These sets of guides are adapted to slidably support the slides 60, 61 and 62 adapted for sliding movement in said sets of guides through 40 the respective horizontally disposed slots 19, 20 and 21 in the vertical partition 14 against the strips 63', disposed to limit the outward movement of the slides and to co-operate therewith for the purpose of preventing the balls dropping on the slides from accidentally leaving the casing. The outer ends of these slides 60, 61 and 62 are preferably concaved as shown to facilitate diverting the balls onto the respective shelves with which the slides co-operate. Any suitable means may be provided for projecting these slides 60, 61 and 62 across the passage-way D. In one embodiment of the invention the slides are projected across 45 the passage-way and retracted therefrom through the instrumentality of a series of levers. In this particular embodiment of slide operating means, the levers are each adapted to lift the lever 38 to release the balls from the guide-way C and simultaneously to project a slide across the passage-way to release the ball in its movement through the passage-way and to divert the ball onto the shelf selected or desired to take the ball or balls as the case may be. 50

Assuming that a player who has selected shelf 29 as his rack to receive the balls made by him during the progress of the game and the player has shot one ball into a pocket which has found its way into the guide-way C and been arrested therein by the gate 35 and this particular player desires to rack the ball made by him, he will actuate the lever 63 projecting through the front of the casing at the upper portion thereof. This 55 lever 63 is pivoted on a shaft 64 secured in the partition 57 and the side 13 of the casing B and has an extension 65 whose free end is loosely fitted in a slot 66 in the slide 60. The upward thrust of the lever 63 in its 60 guide 63' causes it to engage the under side of the weighted part 38' of the lever 38 and lift the same. At the same time, the extension 65 of the lever 63 causes the forward movement of the slide 60, resulting in the 65 slide 60 being projected across the passage-way D into co-operative relation with the respective strip 63'. The gate 35 being carried by the lever 38 the upward movement of the lever causes the gate to be opened at 70 the same time that the slide 60 is projected across the passage-way D. The ball 12' in the guide-way C is then permitted to pass through the opening 26 into the passage-way D. The ball engaging the slide 60 is 75 thereby diverted onto the shelf 29 and rolls on the latter until it engages the gate 42 or another ball in engagement with the gate 42, where it remains until it is desired to take the balls off the shelf 29 over the side 80 edge thereof, or permit them to pass through the opening 32 in the shelf 29, in which event, it, or as many balls as were on the shelf 29, would pass through openings 33 and 34 and out through the opening 56 in 85 the side 12 of the casing. Assuming that the next player shooting has selected shelf 30 as his rack and assuming that he has shot one or more balls into the pockets of the table and that the same has rolled to the 90 guide-way C, the former player has released his hold on the lever 63 and the weighted end 38' of the lever 38 has caused it, the gate 35, and the slide 60 to assume normal positions, the second player gives an upward 95 thrust to the short operating lever 67 in its guide 67'. The lever 67 is pivoted on the shaft 68 supported by the partition 57 and the side 13 of the casing. This operating lever 67 has an extension 69 which 100

passes through a slot 70 in the slide 60 and engages in a slot 71 in the slide 61. The upward thrust of the operating lever 67 causes the slide 61 to be projected across the 5 passage-way D in the same manner as described with relation to the slide 60, and at the same time the lever 38 and the gate 35 are raised, as in the manner before described. The ball or balls then entering the 10 passage-way D through the opening 26 are diverted by the slide 61 onto the shelf 30 in the same manner as described in connection with the balls being diverted onto the shelf 29. The third player, or any other 15 player who may select shelf 31, when he has shot a ball or balls into pocket or pockets of the table A and when he desires to rack them on the shelf 31, gives an upward thrust to the short operating lever 72 in its 20 guide 72'. The lever 72 is pivoted on a shaft 73 mounted in the partition 57 in the side 13 of the casing B. This operating lever 72 has an extension 74 which passes through a slot 75 in the shelf 60 and through a slot 76 in the shelf 61 and engages in a 25 short slot 75 in the shelf 62. The upward thrust of the lever 72 in the manner stated causes the projection of the slide 62 across the passage-way D and a simultaneous upward movement of the lever 38 and an upward movement of the guide 35, permitting the ball to enter the passage-way D and be arrested therein by the slide 62 and diverted onto the shelf 31 as should now be well understood. 30

In the event that it be desired to release the balls from the guide-way C and permit them to pass entirely through the passage-way D onto the shelf 22, it is simply necessary to manipulate the lever 77 by giving it an upward thrust in its guide 77'. The lever 77 is pivotally mounted on the aforesaid shaft 68. This lever 77 has not an extension and is not connected to any slide. 40 It is formed and arranged so that an upward thrust thereon will lift the weighted end 38' of the lever 38 and thereby lift the gate 35. This actuation permits the ball or balls in the guide-way C to pass entirely 45 through the guide-way D and roll down the shelf 22 toward the opening 56. The balls diverted onto the shelf 22 may be arrested by the gate 45. By opening the gate 45, either by manipulating it in the slot 51 or 50 by actuation of the strip 52, the ball or balls on the shelf 22 may pass out through the opening 56 in the side 12 of the casing. All of the balls at the same time may be permitted to roll off the respective shelves and 55 pass through the respective openings and out through the opening 56 in the side 12 of the casing, either by separate manipulation of the gates 42, 43, 44 and 45, or by a simultaneous manipulation thereof through 60 an upward movement of the strip 52. 65

The contrivance illustrated is but one embodiment of my invention. It is not my intention to limit myself to the number of shelves employed for the racking of the balls of the various players. The shelf 22 70 is designed to perform all of the functions of the shelves 29, 30 and 31. In other words, the shelf 22 is not designed solely to provide a means whereby a ball may be passed entirely through the contrivance. 75 Any ball may be readily removed from any of the racks and, as stated, shelf 22 is intended to be used in the same manner as any of the other shelves, and, in the use of a device constructed in accordance with 80 the present drawings, this shelf 22 would be used by a fourth player, the same as the other players would use the shelves thereabove. Obviously, any number of shelves may be employed and in the employment 85 of more than four shelves there would be employed the necessary additional number of levers, slides and other actuating parts to divert balls from the passage-way onto the respective shelves according to the number 90 of shelves employed in the contrivance. To these ends I have worded the appended claims accordingly and they are to be construed with the thought in mind that I am not limiting myself either to the number 95 of shelves or the number of levers for diverting balls from the passage-way onto the respective shelves and that, while I may direct a ball or balls entirely through the contrivance, this is only an incident to my 100 invention and not necessarily essential thereto.

From the foregoing it will be seen that I provide a simple, inexpensive, durable and efficient appliance which may be easily and 105 readily actuated to effectively rack the balls selectively on various shelves and that the actuating parts return automatically to normal positions after actuation and are released by the manipulator. It will also be apparent that the balls may be easily and quickly unracked or discharged from my improved appliance into a container (not shown) disposed to receive the balls from the appliance when discharged therefrom. 110 While the passage-way D may be considered in the light of a chute or a "ball-drop," I have intentionally termed it a passage-way, with the understanding that it is not my intention to limit myself to the exact 115 structure disclosed for that I contemplate making changes in the structure disclosed in so far as I may be permitted to do so under the terms and scope of the appended claims. 120

What is claimed is:—

1. A pocket billiard or pool rack comprising a casing having a ball passage-way therein, spaced shelves in the casing having communication with said passage-way, the 130

casing having a discharge opening therein adjacent the lowermost shelf, each shelf having a discharge opening therein, means whereby the balls may be delivered to said 5 passage-way and simultaneously directed onto the shelves selectively, a gate arranged in advance of each of the discharge openings of the shelves, and means whereby the gates may be operated to permit the passage 10 of the balls through the discharge openings of the shelves and out of the discharge opening in the side of the casing.

2. A pocket billiard or pool rack comprising a casing having a ball passage-way therein, spaced horizontally disposed shelves in the casing having communication at one of their ends with said passage-way, the casing having a discharge opening in one side thereof adjacent the lowermost 20 shelf, each shelf having a discharge opening therein at one end thereof, means whereby balls may be simultaneously delivered to said passage-way and directed onto the shelves selectively, and means whereby the 25 balls may be arrested in movement on the shelves to prevent discharge thereof from the shelves through the discharge openings of the shelves.

3. A pocket billiard or pool rack comprising a casing having a ball passage-way therein, spaced horizontally disposed shelves in the casing having communication at one of their ends with said passage-way, the casing having a discharge opening 30 in one side thereof adjacent the lowermost shelf, each shelf having a discharge opening therein at one end thereof, means whereby balls may be simultaneously delivered to said passage-way and directed onto the shelves selectively, means whereby the 35 balls may be arrested in movement on the shelves to prevent discharge thereof from the shelves through the discharge openings of the shelves, and means whereby the latter 40 means may be operated separately with relation to each shelf or simultaneously with relation to all of the shelves.

4. An appliance of the character described comprising a casing having a vertically disposed ball passage-way therein, spaced horizontally disposed shelves in the casing having communication with said passage-way, the casing having a discharge opening 45 in one side thereof adjacent the lowermost shelf, each shelf having a discharge opening therein at one end, means whereby the balls may be delivered to said passage-way and diverted onto the shelves selectively, a gate arranged adjacent the 50 discharge opening of each shelf to arrest movement of the balls on the respective shelves, said gates being operable independently one of another, and means whereby all of said gates may be operated simultaneously so that the balls may be dis- 55

charged through the discharge openings of the latter and out through the discharge opening in the side of the casing.

5. An appliance of the character described comprising a casing having a ball passage-way therein, a shelf in the casing having communication with said passage-way, the casing having a discharge opening therein, a guide-way leading to and communicating with said passage-way, a 70 gate for said guide-way, means to operate the gate to permit the passage of a ball from the guide-way into the passage-way and onto said shelf and out through the discharge opening in the casing. 80

6. An appliance of the character described comprising a casing having a ball passage-way therein, a shelf in the casing having communication with said passage-way, the casing having a discharge opening therein, a guide-way leading to and communicating with said passage-way, a 85 gate for said guide-way, means to operate the gate to permit the passage of a ball from the guide-way into the passage-way and onto said shelf, a gate disposed adjacent the discharge opening in the casing to arrest movement of the ball on said shelf, 90 said gate being operable to permit passage of the ball off of the shelf out through the discharge opening in the side of the casing. 95

7. A rack of the character described comprising a casing having a ball passage-way therein, a guide-way having communication with said passage-way, a lever pivoted in the casing, a gate connected to the lever and normally closing said guide-way, the free end of the lever being weighted to normally move downward and thereby normally maintain the gate in closed position with relation to the guide-way, a plurality of spaced shelves in the casing having communication with said passage-way, each shelf having a discharge passage 100 therein, the casing having a discharge opening therein adjacent the lower-most shelf, a plurality of slides slidably mounted in the casing in substantially horizontal alignment with the shelves for projection into and out of the passage-way, and means 105 whereby the lever and gate may be lifted and one of the shelves projected into said passage-way whereby the balls may enter the passage-way from the guide-way and be diverted onto one of said shelves, means 110 for temporarily arresting movement of the balls on such shelf, and means whereby said arresting means may be manipulated to permit discharge of the balls through the openings of the shelves and out through the discharge opening in the casing. 115

8. An appliance of the character described, comprising a casing, a vertical partition in the casing adjacent one side thereof and spaced slightly therefrom to form 120

a vertical passage-way, a horizontal partition in the upper portion of the casing having an opening leading into said passage-way, a guide-way on said horizontal partition, a gate slideable vertically in the guide-way, a lever pivoted in the casing and connected to said gate, the free end of the lever being enlarged and lying over the opening in said horizontal partition, 10 the enlarged end of the lever weighting the free end of the latter to maintain the gate of the guide-way normally in closed position, a plurality of spaced shelves mounted in the casing, the aforesaid vertical partition having openings therein to establish communication between the shelves and said passage-way, the casing having a discharge opening in one side adjacent the lower-most shelf, a plurality of slides 15 mounted to be projected into and withdrawn from said passage-way opposite the shelves, each shelf having a discharge opening therein, a plurality of members pivoted in the casing to form gates to prevent the 20 passage of balls off the shelves through the discharge openings thereof, means constructed and arranged to operate said slideable gate and to project one of said slides into said passage-way so as to permit the 25 delivery of a ball from the guide-way into said passage-way and to divert said ball onto the shelf opposite that into alignment with which said slide has been projected, and means whereby the pivoted member 30 which co-operates with the shelf on which said ball has been placed may be operated to permit discharge of the ball off such shelf through the discharge openings in the shelves and out of the opening in the 35 side of the casing.

9. An appliance of the character described, comprising a casing having a passage-way therein, spaced shelves in the casing, the spaces between which communicate 40 with said passage-way, the casing having a discharge opening therein adjacent the lower-most shelf, each shelf having a discharge opening therein, and means whereby a ball may be delivered to said passage-way and permitted to pass entirely therethrough onto the lower-most shelf, and means whereby a ball may be delivered from the guide-way into said passage-way and diverted onto the shelves selectively.

10. An appliance of the character described, comprising a casing having a passage-way therein, spaced shelves in the casing, the spaces between which communicate with said passage-way, the casing having a discharge opening therein adjacent the lower-most shelf, each shelf having a discharge opening therein, means whereby a ball may be delivered to said passage-way and permitted to pass entirely there- 50 through onto the lower-most shelf, means

whereby a ball may be delivered from the guide-way into said passage-way and diverted onto the shelves selectively, means for temporarily arresting movement of the balls on the shelves, and means whereby the arresting means may be manipulated to permit of discharge of balls from the shelves through the discharge openings thereof. 70

11. An appliance of the character described, comprising a casing having a passage-way therein, spaced shelves in the casing, the spaces between which communicate with said passage-way, the casing having a discharge opening therein adjacent the lower-most shelf, each shelf having a discharge opening therein, means whereby a ball may be delivered to said passage-way and permitted to pass entirely therethrough onto the lower-most shelf, means whereby a ball may be delivered from the guide-way 80 into said passage-way and diverted onto the shelves selectively, means for temporarily arresting movement of the balls on the shelves, and means whereby the arresting means may be manipulated to permit of discharge of balls from the shelves through the discharge openings thereof or whereby the balls may be discharged from any one of the shelves independently of discharge of balls from any other of the shelves. 90

12. An appliance of the character described, comprising a casing having a ball passage-way therein, a guide-way in the casing having communication with said passage-way, a gate normally holding the balls 100 in the guide-way, a lever pivoted in the casing and to which said gate is connected, the casing having a discharge opening, and means for engagement with the lever to lift the same and thereby lift said gate to permit the passage of the balls from the guide-way into the passage-way. 105

13. An appliance of the character described, comprising a casing having a ball passage-way therein, a guide-way in the 110 casing having communication with said passage-way, a gate normally holding the balls in the guide-way, a lever pivoted in the casing and to which said gate is connected, the casing having a discharge opening, means for engagement with the lever to lift the same and thereby lift said gate to permit the passage of the balls from the guide-way into the passage-way, and means to temporarily prevent discharge of the balls through the discharge opening of the casing. 115

14. An appliance of the character described comprising a casing having a ball passage-way therein, a guide-way in the casing which has communication with the passage-way, a lever pivotally mounted in the casing and having its free end enlarged to weight the same so as to maintain the lever normally in its lowered position, a gate slideable in the guide-way and having communi- 125 130

cation with said lever, and means for lifting the lever and the gate to permit the passage of the balls from the guide-way into the passage-way, the casing having a ball discharge opening.

15. An appliance of the character described comprising a casing having a ball passage-way therein, a guide-way in the casing which has communication with the passage-way, a lever pivotally mounted in the casing and having its free end enlarged to weight the same so as to maintain the lever normally in its lowered position, a gate slideable in the guide-way and having communication with said lever, means for lifting the lever and the gate to permit the passage of the balls from the guide-way into the passage-way, the casing having a ball discharge opening, and a gate operable to arrest movement of the balls in the casing after their discharge from the guide-way and which may be operated to permit discharge of the balls through said discharge opening.

16. An appliance of the character described comprising a casing having a ball passage-way therein, a guide-way in the casing having communication with said passage-way, a gate normally holding the balls in the passage-way, a shelf in the casing hav-

ing communication with the passage-way, a slide adapted to be projected across said passage-way to direct balls from the passage-way onto the shelf, means for operating said slide, and means for operating said gate to permit the passage of balls from the guide-way into the passage-way.

17. An appliance of the character described comprising a casing having a ball passage-way therein, a guide-way in the casing having communication with said passage-way, means normally holding the balls in the passage-way, a plurality of shelves having communication with said passage-way, a plurality of slides adapted to be projected across the passage-way to direct balls onto the respective shelves, means for operating said slides separately to direct balls from the passage-way onto the respective shelves, and means to operate said holding means in the guide-way to permit balls to pass from the guide-way into the passage-way.

In testimony whereof I affix my signature in the presence of two witnesses.

A. FAYEL WHEELER.

Witnesses:

JNO. C. ALLAN,
W. S. S. SAXTON.
